VACUUM CLEANER NOZZLE

Donald F. Amend, Milwaukee, Wis.

Application January 30, 1953, Serial No. 23,347

Term of patent 14 years

(Cl. D9—2)

To all whom it may concern:

Be it known that I, Donald F. Amend, a citizen of the United States, residing at Milwaukee, State of Wisconsin, have invented a new, original, and ornamental Design for a Vacuum Cleaner Nozzle, of which the following is a specification, reference being had to the accompanying drawing, forming a part hereof.

Fig. 1 is a top view in elevation of a vacuum cleaner nozzle embodying my new design.

Fig. 2 is a side view in elevation of the same.

Fig. 3 is a bottom view in elevation of the same.

Fig. 4 is a view on line 4—4 of Fig. 1.

I claim:

The ornamental design for a vacuum cleaner nozzle, as shown.
